UNITED STATES PATENT OFFICE.

EMORY CROUSE, OF WICHITA, KANSAS.

ROTARY PUMP.

Application filed September 22, 1921. Serial No. 502,323.

To all whom it may concern:

Be it known that I, EMORY CROUSE, a citizen of the United States, residing at Wichita, county of Sedgwick, and State of Kansas, have invented certain new and useful Improvements in Rotary Pumps; and I do declare the following to be a full, clear, and exact description of the invention, such as will enable others skilled in the art to 10 which it appertains to make and use the same, reference being had to the accompanying drawings, and to the characters of reference marked thereon, which form a part of this specification.

15 This invention relates to pumps and has special reference to rotary pumps of the type employed for pumping liquids.

It is the object of this invention to produce a rotary pump that shall be simple to 20 construct, which can be readily assembled and which will be adapted to handle large quantities of liquid. It is also my object to produce a pump of large capacity compared to its size and therefore specially 25 adapted to be employed in places where the space is limited.

In order to more clearly describe my invention I shall refer to the accompanying drawing in which—

30 Fig. 1 is a side elevation of my pump fully assembled.

Fig. 2 is a section on line 2—2 Fig. 3.

Fig. 3 is a section on line 3—3 Fig. 1 and

35 Fig. 4 is a longitudinal section taken on line 4—4 Fig. 3.

The same reference characters will be used to indicate the same parts throughout the several views.

40 My improved rotary pump comprises an annular body portion 1, a rear side portion or plate 2, a front side portion or plate 3, a rotor 4 and a plurality of movable plates, together with other parts which will be hereinafter pointed out.

45 Annular body portion 1 has an intake port 7 which is provided with an extension 8 of considerable length and diametrically opposite port 7 is an exhaust port 9 which is also provided with an extension 10, extensions 8 and 10 being separated by an arcuate portion 11 which is adapted to make a water tight sliding fit with the outer surface of rotor 4, in the manner indicated in Figs. 2 and 4. The rear side or plate 2 is provided 55 with an outwardly projecting hollow portion 12 which serves as a bearing for the rotor

shaft 13 the inner surface of plate 2 having a circular projecting portion 14 which is concentric with the inner circular opening of the body portion 1 but eccentric with respect to the bearing in projection 12 all as shown in Fig. 2. The front side plate 3 has an outwardly projecting tubular member 15 and a bearing 16 for shaft 13, tubular member 15 serving as a gland or packing box and containing suitable packing material 17 which is compressed by the inner end of bearing 18 which is provided with an outwardly extending flange 19 and which is held in position by a screw threaded cap 20 (Fig. 3). The 70 rotor 4 is of smaller diameter than the opening in member 1 and is mounted eccentrically so that its outer surface engages the curved part 11 as above stated. Each side of the rotor 4 has an annular flange 21 which fits snugly against the inner surface of sides 2 and 3 (Figs. 2 and 3). Rotor 4 is provided with a plurality of spaced slots 22 the leading sides of which are substantially radial (Fig. 4). Slideable in said slots 22 are 80 plates 23 whose outer sides are held in contact with the inner surface of body member 1 and whose ends are in close but sliding contact with the inner surfaces of plates 2 and 3 (Fig. 3). For the purpose of causing 85 plates 23 to reciprocate in slots 22 and contact with the inner surface of body member 1, I have provided two rings 24 one of which surrounds the circular projection 14 on plate 2 and the other of which surrounds the corresponding circular projection 25 on plate 3 (Fig. 3). The inside diameters of rings 24 is slightly greater than the outside diameters of projections 14 and 25 (Fig. 2). Projections 14 and 25 are each provided with two 95 holes angularly arranged with respect to each other. Hole 26 is radial and extends in the direction of the greatest eccentricity with respect to shaft 13. The other hole 27 is spaced at an angle of substantially sixty 100 degrees from hole 26. Within each hole is a spring 28 and a ball 29. The balls 29 engage the inner surface of ring 24 and holds the same in an eccentric position with respect to projections 14 and 25 all as shown in Fig. 105 2. Plates 23 engage the outer peripheries of rings 24 and are so related in size to the other parts that when they occupy positions to the left of the central vertical line of Figs. 2 and 4 they will move the rings 24 against 110 the tension of springs 28 and in this manner their outer edges are held in close contact

with the inner surface of member 1. Sides 2 and 3 are held in place on member 1 by means of a plurality of bolts 30 which project through holes 31 in ears 32. I have shown two removable side plates 2 and 3 but if it is found desirable body member 1 and side plate 2 may be made integral. Pipes 33 and 34 can be connected respectively with the intake and the exhaust ports 7 and 9.

10 In Fig. 1 I have shown a handle 35 for turning the rotor 4 but it is obvious that I may operate the pump by other power if I so desire.

The operation of my pump is as follows.

15 Handle 35 is rotated in a clockwise direction and through the medium of shaft 13 rotates the rotor 4 in the same direction. Rings 24 keep plates 23 in close contact with the inner walls of body member 1. As each 20 plate 23 passes the intake port 7 it produces a suction which causes the atmospheric pressure to force liquid through pipe 33 into the pump; the liquid is carried along by plates 23 and discharged through port 9 in the manner well known in rotary pumps.

25 I am aware that pumps have been made which embody the broad idea of a circular chamber containing an eccentrically placed rotor carrying a number of valve plates, but 30 I believe that I am the first one to employ my specific means for keeping the plates in contact with the inner cylindrical surface and to compensate for wear.

Having now described my invention what I claim is—

1. In a rotary pump having a cylindrical chamber, a rotor mounted eccentrically therein, a plurality of substantially radial slots in said rotor, plates slidably mounted in said slots, means for yieldingly holding said plates against the inner surface of said chamber said means comprising a pair of inwardly extending circular projections concentric with respect to said chamber, a ring surrounding each circular projection and having a greater internal diameter than the diameter of said projections, resilient means on one side of said projections for engaging the inner surface of said rings and means on 45 said plates for engaging the outside of said rings.
2. A rotary pump comprising a cylindrical chamber having an intake and an exhaust port, an inwardly extending circular projection on each side of said chamber and concentric therewith, a rotor eccentrically mounted within said chamber and provided with circular flanges on each side for en-

gaging the sides of the chamber, a plurality of substantially radial slots in said rotor, 60 plates slideable in said slots, a ring surrounding each circular projection and engaging said plates and resilient means between said projections and said ring.

3. A rotary pump comprising a cylindrical chamber having an intake and an exhaust port, an inwardly extending circular projection on each side of said chamber and concentric therewith, a rotor eccentrically mounted within said chamber and provided with circular flanges on each side for 65 engaging the sides of the chamber, a plurality of substantially radial slots in said rotor, plates slideable in said slots, a ring loosely surrounding each circular projection and engaging an end of said plates and resilient means on one side of said projections for 70 engaging the interior of said rings.

4. A rotary pump comprising a cylindrical chamber having an intake and an exhaust port, an inwardly extending circular projection on each side of said chamber and concentric therewith, a rotor eccentrically mounted within said chamber and provided with circular flanges on each side for 80 engaging the sides of the chamber, a plurality of substantially radial slots in said rotor, plates slideable in said slots a ring loosely surrounding each circular projection and engaging an end of said plates, a plurality 85 of angularly spaced springs on one side of said projections and engaging with the interior of said rings whereby said rings will hold said plates yieldingly against the inner surface of said cylindrical chamber.

5. A rotary pump comprising a cylindrical chamber having an intake and an exhaust port, an inwardly extending circular projection on each side of said chamber and concentric therewith, a rotor eccentrically mounted within said chamber and provided with circular flanges on each side for 95 engaging the sides of the chamber, a plurality of substantially radial slots in said rotor, plates slideable in said slots, a ring loosely surrounding each circular projection and engaging an end of said plates, a plurality 100 of angularly spaced springs on one side of said projections and engaging with the interior of said rings whereby said rings will hold said plates yieldingly against the inner surface of said cylindrical chamber, and balls between the ends of said springs and the interior of said rings.

In testimony whereof I affix my signature.

EMORY CROUSE.
